UNITED STATES PATENT OFFICE.

GERARD JOHAN LUGT, OF AMSTERDAM, NETHERLANDS.

CRUSHING AND CRACKING MACHINE.

1,321,652.

Specification of Letters Patent. Patented Nov. 11, 1919.

Application filed December 20, 1918. Serial No. 267,674.

To all whom it may concern:

Be it known that I, GERARD JOHAN LUGT, subject of the Queen of the Netherlands, residing at Amsterdam, Kingdom of the 5 Netherlands, have invented certain new and useful Improvements in Crushing and Cracking Machines, of which the following is a specification.

This invention relates to a crushing and 10 cracking-machine of the kind in which, of two groups of crushing and cracking elements, all elements of one group rotate with the same velocity on one axle and all elements of the other group rotate on a second 15 axle.

The crushing and cracking-machine according to the present invention is characterized by its simple construction and great capacity.

20 A further feature of the present invention consists therein that the degree of compression of the material to be cracked can be regulated and that when materials of different volumes are simultaneously cracked, the 25 compression of said materials can be adjusted according to the dimensions of the materials treated.

These results are obtained by arranging 30 the crushing or cracking elements in such way, as to cause each crushing and cracking-element of one group to coöperate with a crushing and cracking-element of the other group, while all crushing and cracking elements of one group rotate with the 35 exclusion of any other movement on one axle and those of the other group rotate also with the exclusion of any other movement on a second axle. This second axle is disposed in alinement with the first one, and 40 both axles lie within the circles described by the outer ends of both groups of crushing and cracking elements. The said axles being arranged in such way that within each revolution the coöoperating crushing and 45 cracking elements are once approaching to and once moving away from each other.

According to the present invention the coöoperating crushing and cracking elements approach each other while describing an 50 angle of 180 degrees and move away from each other while describing the subsequent 180 degrees of the circle of revolution.

An advantage obtained by this invention 55 consists in providing for the degree of compression to be altered at different ways,

In the accompanying drawings, illustrating one embodiment of my invention:

Figure 1 represents a vertical longitudinal section of the machine on the line A—B of Fig. 2.

60 Fig. 2 represents a vertical cross section of the same on the line C—D of Fig. 1.

Fig. 3 represents a similar view through the gearing 8 and 9 and proximate parts on the line E—F of Fig. 1, the shaft 10 being 65 shown in elevation.

Fig. 4 represents a detail view in perspective of the crushing and cracking elements 5 arranged in such a manner on the hub 3 that the crushing surfaces lie in planes passing longitudinally through the axes of rotation.

A pair of supporting standards 1 provided with sockets have a shaft 2 (Figs. 1 to 3) fixed in the latter, said shaft consisting 70 of two elements or sections mounted end to end in approximate alinement with, but eccentric to, each other and bearing respectively hubs 3 and 4 which rotate thereon. Hub 3 carries the crushing and cracking elements 5, while hub 4 carries the crushing and cracking elements 6, the latter having their outer ends shaped into curved spoon-like scoops 14. The shafts or shaft sections constitute supporting axles for the series of 80 elements. These groups of elements 5 and 6 are provided respectively with circular series of cog teeth constituting racks 7, which mesh respectively with cog gear wheels 8 and 9 carried by a driving shaft 85 10 rotatably mounted in bearings 11 on supporting standards 1, this shaft being driven by any convenient means; for example, by a pulley and the coöperating belt.

The wheel 8 is fastened to shaft 10 by a 90 pin 12 strong enough to bear the strain of a predetermined load, but adapted to break when this load is exceeded.

As shown in Fig. 4, the crushing and cracking elements may lie in the planes 100 passing longitudinally through the axes of rotation.

The crushing and cracking operation takes place as follows:

As shown in Figs. 1 and 2, the hubs 3 105 and 4 are placed end to end in such a way that each crushing and cracking element 5 lies between two crushing and cracking elements 6, and vice versa, for the purpose of causing each crushing and cracking element 110

5 to coöperate with a crushing and cracking element 6 and of effecting the crushing between the crushing and cracking surfaces of the overlapping parts of the crushing and cracking surfaces 6.

As shown in Fig. 1, the space between the coöperating crushing and cracking elements 5 and 6 is the greatest when the said elements are in the position marked *c* and the 10 said spaces are diminishing during the rotation of said elements in the direction marked by an arrow in Fig. 1; the said spaces becoming the smallest after said elements having reached the position marked *d*; from here the said spaces gradually increase till the crushing and cracking elements have again attained the position marked *c*.

During the rotation of the crushing and 20 cracking elements from the position *c* into the position *d* the spaces between the coöperating elements are first filled with materials caught by the catchers, whereafter the said materials are crushed and cracked, 25 and during the rotation of the crushing and cracking elements from *d* to *c* the crushed and cracked materials are first removed from the spaces formed by the coöperating elements, whereafter fresh materials to be treated are caught by the catchers 14.

When the spaces between the coöperating crushing and cracking elements are filled with the materials to be treated at that moment at which said elements are in the 35 position marked *c*, the greatest compression is attained, for in that case the materials to be treated are compressed while the crushing and cracking elements are traveling through the sector of an angle of 180 degrees. If, on the contrary, the spaces between the coöperating crushing and cracking elements are only filled when said elements have reached the position marked *e* in Fig. 1; the angle between the positions *c* 40 and *e* being, say, 60 degrees, the said materials are only compressed while the crushing and cracking elements are traveling through the sector of 180—60 120 degrees; or, in other words, the materials treated are 45 compressed to a smaller degree.

It results from this that the degree of compression can be regulated by altering or adjusting the place where the materials are fed into the machine with regard to the 55 position in which the space between the coöperating crushing and cracking elements is the greatest.

On the other hand, when using a feeding device rigidly fixed to the framework of the 60 machine and not possessing slidable shells 18, or means working in a similar way, the degree of compression of the materials treated can also be regulated by varying the position *c* at which the space between the 65 coöperating crushing and cracking elements

is the greatest with relation to the rigidly fixed feeding device.

If, for example, for the purpose of being able to make use of the gravity for the filling and emptying of the spaces between the 70 coöperating elements, the shaft 2 is mounted in its bearings in such a manner that the axle of said shaft and the axles of the two eccentric sections of same all lie in the same vertical plane, then the coöperating elements 75 will approach each other during the rotation when moving above the horizontal plane passing through the middle of the distance between the axles of the two eccentric sections, and said elements will move 80 away from each other when moving under said horizontal plane.

If now the rigidly fixed feeding place being, of course, left unchanged, the shaft 2 is turned in its bearings over an angle of, 85 say, 30 degrees, then the plane going through the axis of said shaft 2 and through the axes of the two eccentric sections of said shaft, as well as the plane passing through the middle of the distance between the axes 90 of the two eccentric sections, and standing perpendicular on the first mentioned plane, will also be turned 30 degrees.

In consequence thereof, the points from which the coöperating elements start for the 95 purpose either to approach or to move away from each other will be altered in such way that the line connecting said points will form an angle of 30 degrees with the said horizontal plane, and the point in which the space between two coöperating elements is 100 the greatest will be displaced in relation to the unchanged feeding place with 30 degrees.

The degree of compression of a whole 105 charge may, therefore, be regulated either by displacing the feeding place or by turning the shaft 2 in its bearings.

In order, however, that on the bigger materials of a given charge a greater compressing action may be exercised than to the smaller ones; in other words, in order to regulate the degree of compression according to the dimensions or to the size of the materials to be treated, according to this invention the velocity of rotation of the coöperating crushing elements is varied.

Due to the fact that each crushing element 5 forms a kind of hopper with the coöperating crushing element 6, the larger sized 110 materials are already clamped and subjected to compressing or crushing action while being fed or filled into the said hopper, while the other materials, due to their smaller size, are falling down into the lower spaces 115 of said hopper and are only compressed and finely crushed at the inner ends of the said coöperating elements. As these coöperating elements in the meantime have continued their rotation, the compression or crushing 120

of the smaller materials only begins when, after the compression of the bigger materials have started, the crushing and cracking elements have rotated or have described 5 a certain angle.

The size of said angle depends on the velocity of rotation of the crushing elements; at a slow rotation the said coöperating elements will only describe a small angle and 10 the smaller materials will thus rapidly fall through, due to their own weight. In case, however, of the coöperating elements rotating with great velocity, the angle described by the coöperating crushing and cracking 15 elements is greater and the centrifugal force produced is neutralizing the action of the gravity.

Having thus described my invention, what I claim as new and desire to secure by Letters Patent is:

1. In a machine of the kind and for the purpose set forth, two axles arranged end to end, but eccentric to each other, in combination with two opposed rotary series of coöperating crushing elements, supported by 25 said axles, the elements of said two series being arranged alternately with the elements of one series overlapping those of the other series and the eccentricity of said axles 30 being arranged to bring the crushing elements of the two series nearer to each other during a part of the rotation and to gradually separate them during the remainder of the rotation.

2. In a machine of the kind and for the purpose set forth, a shaft having two sections arranged end to end, but eccentric to each other, in combination with two hubs mounted on said sections which serve as their axles, two rotary series of opposed coöperating alternately arranged crushing elements carried by said hubs, and means for rotating said hubs severally but at the same velocity, the eccentricity of the shaft sections being arranged to bring the crushing 45 elements of the two series gradually nearer to each other during a part of the rotation and to gradually separate them during the remainder of the rotation.

3. In a machine of the kind and for the purpose set forth, two axles arranged end to end, but eccentric to each other, in combination with two rotary series of opposed crushing elements supported by said axles, two circular series of cog teeth turning with 55 said series of crushing elements respectively, a shaft carrying a pair of gear wheels which mesh with said series of cog teeth respectively, one of said gear wheels being fastened to said shaft by means of a pin which will 60 give way under a predetermined strain.

In testimony whereof I have affixed my signature in presence of two witnesses.

GERARD JOHAN LUGT.
